(57) **CLAIM**

The ornamental design for a cable housing, as shown and described.

DESCRIPTION

FIG. 1 is a perspective view of a cable housing showing my new design;

FIG. 2 is a similar perspective view thereof with the lid removed;

FIG. 3 is a top perspective view thereof;

FIG. 4 is an enlarged fragmented perspective view thereof;

FIG. 5 is a bottom perspective view of the lid of FIG. 1; and,

FIG. 6 is a top perspective view thereof.

The broken lines shown represent unclaimed subject matter and form no part of the claimed design.
